TELEPHONE SYSTEM

Edward S. Peterson, Elmwood Park, Ill., assignor,
by mesne assignments, to Associated Electric
Laboratories, Inc., Chicago, Ill., a Corporation
of Delaware

Application November 30, 1931
Serial No. 577,933

9 Claims. (Cl. 179—27.)

The present invention relates in general to telephone systems, and more particularly to automatic telephone systems in which access may be had to operators' positions for information calls, call recording, or other similar services.

Trunks to special service operators are usually taken from the banks of selectors, such as special second selectors. In a large exchange there are 10 a number of groups of these selectors and, in order to properly distribute the traffic, the trunks from the selector levels may terminate in rotary hunting switches which in turn have access in common to the special service trunks.

15 The main object of the present invention is to provide a rotary hunting switch suitable for use on such special service trunks or in other cases where a similar hunting switch is required.

According to a particular feature of the invention, after the switch has been operated to select 20 an idle trunk, it may be restarted to select a different idle trunk by momentarily removing ground from the release trunk conductor of the seized trunk; and provision is made for the holding 25 of the preceding switch train during the time that the switch is re-operated to find a different idle trunk.

The above and other objects and features of the invention will best be understood from a 30 perusal of the following specification when read in connection with the accompanying drawing, comprising one figure only, which shows, by means of the usual schematic diagram, only sufficient of the apparatus in a telephone exchange 35 to enable the present invention to be understood.

Referring to the drawing, the lineswitch LS is mechanically similar to the well-known rotary lineswitch used in automatic telephony in which the wipers are advanced when the rotary magnet 40 is deenergized. The switch is of the so-called homing type, that is, the switch always returns to its normal or home position after being released. Lineswitches such as LS are accessible from selector levels, the lineswitch LS 45 being accessible over trunk conductors 1, 2, and 3. A number of these switches may be provided, all of which have access in common to trunks extending to special service operators' positions, of which position No. 1 is shown somewhat in 50 detail and position No. 2 is indicated by the rectangle in the lower portion of the drawing. A number of these operators' positions may be provided depending upon the traffic conditions. Trunks from the banks of the rotary lineswitches 55 may be distributed to the several operators' posi-

tions in several ways. For example, if there are three operators' positions provided, the first, fourth, seventh, etc., trunks may extend to the first operator's position, while the second, fifth, eighth, etc., trunks may extend to the second operators' position, and the third, sixth, ninth, etc., trunks may extend to the third operator's position.

Having given a brief description of the general layout, a detailed description of the operation of 65 the disclosure will now be given.

For this purpose it will be assumed that a calling subscriber desires information and for this purpose has extended a connection through one or more selector switches to the trunk comprising 70 conductors 1, 2, and 3 and extending to the rotary hunting switch LS.

When the trunk comprising conductors 1, 2, and 3 is seized by a selector switch and the subscriber's loop is switched through, ground is 75 sent forward on release trunk conductor 2 at the same time that a circuit is completed for line relay 4 extending from battery, upper winding of relay 4, resting contact of armature 18 and said armature, conductor 1, over the subscriber's 80 loop, to conductor 3, armature 21 and its resting contact, lower winding of line relay 4 to ground. Relay 4 operates and at armature 6 and its working contact grounds the release 85 trunk conductor 2 to hold the switching-through relay of the selector operated.

The release trunk conductor 2 now being grounded, a circuit for the stepping magnet 3 of the lineswitch LS may be traced over the normally closed contacts controlled by armature 90 20, armature 14 and its resting contact, interrupter springs 9 of the rotary magnet, winding of rotary magnet 8 to battery. The rotary magnet 8 energizes in this circuit and upon energizing opens its interrupter contacts 9. However, 95 since contacts 7 are now closed, the interrupter contacts 9 are shunted and magnet 8 remains energized.

When line relay 4 energized, it also completed 100 the circuit for slow-to-operate relay 10 at armature 5 and its working contact. Relay 10 operates after an interval and at armature 16 and its resting contact opens the shunt around interrupter spring 9, allowing the magnet to deenergize and advance the wipers of the switch one 105 step. At armature 11 and its working contact relay 10 connects ground to the lower winding of cut-off relay 17, at armature 12 and its working contact it connects the junction point of the two windings of the cut-off relay to the test 110

wiper 23, at armature 13 and its working contact it connects the rotary magnet to the test wiper 23 through the interrupter contacts 9 of the rotary magnet, at armature 14 and its resting contact it opens the initial operating circuit for the rotary magnet, and at armature 15 and its resting contact it opens the homing circuit of the switch.

The upper winding of cut-off relay 17 is a resistance winding to prevent short-circuiting of the battery and the relay will not energize over this winding. Since the lower winding is short circuited as long as test wiper 23 encounters a grounded bank contact, the relay does not operate until wiper 23 fails to find ground. This shunting circuit of the lower winding extends from ground on the bank contact encountered by wiper 23, armature 19 and its resting contact, armature 12 and its working contact, to the junction point of the two windings of relay 17. This same ground also extends through armature 13 and its working contact, interrupter springs 9 of the rotary magnet, winding of rotary magnet 8 to battery. As long as test wiper 23 encounters busy bank contacts, as indicated by ground potential, rotary magnet 8 is intermittently operated to advance the switch wipers step by step in search of an idle trunk. In operating, rotary magnet 8 interrupts its own circuit at interrupter contacts 9 and, upon de-energizing, it steps the wipers to the succeeding set of bank contacts and at the same time recloses its own circuit at its interrupter contacts.

It will be assumed that the trunk comprising conductors 32, 33, and 34 extending to operator's position No. 1 and accessible over bank contacts 26, 27, and 28 is the first idle trunk encountered by the lineswitch LS. When the rotary magnet 8 deenergizes and steps the wipers 22, 23, and 25 into engagement with bank contacts 26, 27, and 28, there is no ground potential present on bank contact 27 engaged by wiper 23 and, accordingly, the rotary magnet 8 will not again energize. At this time the lower winding of cut-off relay 17 is no longer shunted by ground on the test wiper and the relay operates over both of its windings in series. At armatures 18 and 21 and their respective resting contacts, it disconnects the line relay 4 and, at the working contacts of these armatures, it switches through the trunk conductors 1 and 3 over wipers 22 and 25 to the trunk conductors 32 and 34 extending to the operator's position. At armature 20 and its working contact, it connects ground to release trunk conductor 2 to hold the preceding switches operated and, at armature 19 and its working contact, it connects its two windings in series to test wiper 23.

Line relay 4 deenergizes and, at armature 5 and its working contact, opens the circuit of a slow-acting relay 10; at the normally closed springs controlled by armature 6, it closes a point in the homing circuit of the switch; and, at armature 7 and its working contact, it opens a further point in the shunting circuit of the interrupter springs 9 of the rotary magnet. The relay 10 is made slow to operate by a slug on the armature end of the core, and this also causes the relay to be somewhat slow to release. It, therefore, maintains the ground on the windings of cut-off relay 17 at armature 11 and its working contact for a short interval after line relay 4 has released. During this interval ground is sent back from the trunk circuit extending to the operator's position over test wiper 23 to hold the cut-off relay 17

operated. When relay 10 finally releases, it opens the initial energizing circuit of relay 17 at armature 11 and its working contact, at armatures 12 and 13 and their respective working contacts, it opens the testing circuit and operating circuits of the switch, at armatures 14 and 15 and their respective resting contacts, it completes points in the homing circuit of the switch, and, at armature 16 and its resting contact, it again prepares the shunting circuit for the interrupter springs 9 of the rotary magnet.

When the cut-off relay 17 of the lineswitch LS operated and switched through the subscriber's loop over wipers 22 and 25 and bank contacts 26 and 28 to trunk conductors 32 and 34, the line relay 47 of the trunk circuit operated from battery, upper winding of relay 47, upper left-hand winding of repeating coil 50, conductor 32, bank contact 26 and wiper 22, working contact of armature 18 and said armature, conductor 1, subscriber's loop, conductor 3, armature 21 and its working contact, wiper 25 and bank contact 28, conductor 34, lower left-hand winding of repeating coil 50, lower winding of relay 47 to ground. Relay 47 operates in this circuit and, at armature 48 and its working contact, completes an obvious circuit for the slow-to-release relay 44. At armature 49 and its working contact, it completes the circuit for the call lamp 54 extending from ground, armature 49 and its working contact, resting contact of armature 52 and said armature, lamp 54 to battery. Relay 44 operates and, at armature 45 and its working contact, extends ground from the contacts of the release key RK to the test bank contact 27, thereby busying this trunk in the banks of all the rotary lineswitches having access thereto and also providing a holding ground which extends over wiper 23, armature 19 and its working contact, the two windings of relay 17 in series to battery. This ground is returned from the trunk circuit before the slow-acting relay 10 has had time to release and open the circuit of the cut-off relay 17, as previously mentioned.

The operator at position 1, upon noting the lighted condition of the lamp 54, and being idle at the time, operates her listening key LK, thereby connecting the conductors 59 and 60 extending to her telephone circuit through contacts 56 and 57 of the listening key LK to the windings 125 of the repeating coil 50. The operation of key LK closes contact 58, thereby extending a circuit from ground, armature 46 and its working contact, contact 58 of key LK, winding of relay 51 to battery. Relay 51 operates and, at armature 53 and its working contact, locks itself operated to ground at armature 46, and, at armature 52 and its resting contact, opens the circuit of lamp 54 thereby extinguishing the lamp.

The operator may now converse with the calling subscriber and give him the desired information. At the end of the conversation, she restores her listening key LK, thereby again opening contact 58, but relay 51 is now locked energized to grounded armature 46, and the lamp 54 is now under the control of the calling subscriber. Should the calling subscriber wish to recall the operator, he may operate his switch-hook several times, thereby releasing and re-operating relay 47. Relay 44 is slow to release and does not fall back during the momentary de-energizations of relay 47. When relay 47 releases, it completes the circuit for the call lamp 54 at armature 49 and its resting contact, thereby flashing the lamp to call to the attention of 150

the operator that the calling subscriber wishes to again converse.

When the calling subscriber has obtained all the information he desires, he replaces his receiver, thereby opening the loop circuit extending to relay 47. Relay 47 releases and, at armature 49 and its resting contact, again completes the circuit for call lamp 54, but, since the lamp remains steadily lighted at this time, the operator knows that the subscriber is not signalling her. At armature 48 and its working contact, relay 47 opens the circuit for slow-to-release relay 44. After an interval, relay 44 releases and, at armature 46 and its working contact, opens the locking circuit of relay 51 to allow this relay to release. Relay 51 releases and, at armature 52 and its working contact, opens the circuit of the call lamp 54, thereby extinguishing this lamp. At armature 45 and its working contact, relay 44 removes ground from test bank contact 27, thereby allowing cut-off relay 17 of the lineswitch LS to release.

At armatures 18 and 21 and their respective resting contacts, relay 17 again extends the trunk conductors 1 and 3 to the windings of line relay 4, but this relay does not operate at this time, since the calling loop is open. At armature 19 and its resting contact, relay 17 again prepares the testing and operating circuits of the lineswitch, and at armature 20 it removes ground from conductor 2 and at the normally closed springs controlled by armature 20 it completes the homing circuit of the switch extending from the grounded bank contacts engaged by wiper 24, resting contact of armature 15 and said armature, normally closed springs controlled by armature 6 of relay 4, normally closed springs controlled by armature 20 of relay 17, armature 14 and its resting contact, interrupter contacts 9 of the rotary magnet, winding of rotary magnet 8 to battery.

Rotary magnet 8 energizes and, at interrupter contacts 9, interrupts its own circuit, thereby allowing it to deenergize and advance the wipers one step. The wiper 24 encounters grounded bank contacts until the switch has reached its normal position, and, therefore, rotary magnet 8 continues to operate to step the wipers until ground is no longer present on the bank contact encountered by wiper 24. During the homing operation of the switch the release trunk conductor 2 is grounded from the ground on the bank contact encountered by wiper 24 to maintain the lineswitch LS busy to selectors having access thereto. When the wipers of the switch reach their normal position, wiper 24 no longer finds ground potential, and the rotary magnet 8 remains deenergized. Ground is also removed from release trunk conductor 2, thereby rendering the switch LS available to selectors. All of the apparatus used in the establishment of the call to the operator has now been restored to normal.

It will now be assumed that, when the lineswitch LS has been seized and has operated to seize the trunk line comprising conductors 32, 33, and 34 extending to operator's position No. 1 and the call lamp 54 has been operated at this position, the operator at this position is very busy and does not have time to take care of the call. Upon noting the lighted condition of lamp 54 and desiring to transfer the call to another operator's position, the operator at position No. 1 merely operates release RK for a short interval. This removes the ground from

bank contact 27, thereby removing ground from the windings of the cut-off relay 17 of lineswitch LS. This relay accordingly releases and, at armatures 18 and 21 and their respective resting contacts, again extends the calling loop to the windings of line relay 4. At armature 20 and its working contact it removes one ground connection from the release trunk conductor 2, but this conductor remains grounded from the homing wiper 24 over the resting contact of armature 15 and said armature, and the normally closed contacts controlled by armature 6. At the normally closed springs controlled by armature 20, a circuit is completed from ground on the homing wiper 24, resting contact of armature 15 and said armature, normally closed springs controlled by armature 6, normally closed springs controlled by armature 20, armature 14 and its resting contact, interrupter springs 9 of the rotary magnet, winding of rotary magnet 8 to battery. The rotary magnet 8 energizes in this circuit, but in the meantime the line relay 4 has energized and, at armature 6 and its working contact, has placed direct ground on release trunk conductor 2 and on the above-traced operating circuit for the rotary magnet. At armature 7 and its working contact, it completes the shunting circuit for the interrupter springs through armature 16 and its resting contact. Thus, when the rotary magnet energizes and opens its interrupter springs, it does not immediately release but is held operated over this shunting path.

Line relay 4, in operating, at armature 5 and its working contact completes an obvious circuit for the slow-to-operate relay 10. Relay 10 operates after an interval and, at armature 12 and its working contact, again completes the test circuit from wiper 23 to the junction point of the windings of cut-off relay 17. At armature 16 and its resting contact, it opens the shunt around interrupter springs 9 and, since the springs are now open, the circuit to rotary magnet 8 is opened, and the magnet deenergizes to advance the switch wipers to the next set of bank contacts. At armature 11 and its working contact, it connects ground to the lower winding of relay 17 to shunt the lower winding so that the cut-off relay will not operate if test wiper 23 is engaging a grounded bank contact.

At armature 14 and its resting contact, relay 10 opens a point in the homing circuit of the switch and, at armature 13 and its working contact, it completes the operating circuit for the rotary magnet extending from the test wiper 23, armature 19 and its resting contact, armature 13 and its working contact, interrupter springs 9, winding of rotary magnet 8 to battery. The lineswitch LS is now in hunting condition and hunts for an idle trunk extending to one of the other operators' positions. Since the trunks following the one accessible in bank contacts 26, 27, and 28 go to the other operators' positions in turn, the lineswitch LS will seize one of these trunks to extend the call to one of the other operators' positions. Assuming that the trunk comprising conductors 35, 36, and 37 and accessible over bank contacts 29, 30, and 31 is idle, there is no ground potential present on bank contact 30, and as soon as the rotary magnet 8 deenergizes for the first time to advance the switch wipers from bank contacts 26, 27, and 28, cut-off relay 17 immediately operates and, at armatures 18 and 21 and their respective working contacts, disconnects the line relay 4 and,

at the working contacts of these armatures, switches through the subscriber's loop to operator's position No. 2 over trunk conductors 35 and 37. The remainder of the operation is the same as that previously described in connection with the completed call over trunk conductors 32, 33, and 34.

What is claimed is:

1. In a telephone system, a rotary hunting switch accessible from a preceding selector, a plurality of trunks accessible to said switch and extending to a plurality of operators' positions, respectively, means responsive to the seizure of said switch by the preceding selector for operating it to select an idle trunk extending to one of said operators' positions, means controlled by the operator at said position in case she is too busy to answer the call for causing said switch to select an idle trunk extending to a different operator's position, and means in said switch for holding the preceding selector operated during the time said switch is selecting said second idle trunk.
2. In a telephone system, a plurality of trunk circuits, a hunting switch accessible to a preceding selector and having access to said trunk circuits, means responsive to the seizure of said switch by the preceding selector for operating it to select an idle one of said trunk circuits, a holding circuit for said switch completed by the seized trunk circuit, means responsive to the opening of said holding circuit for causing said switch to select a different idle one of said trunk circuits, and means in said switch for maintaining the preceding selector operated during the time said switch is selecting said different idle one of said trunk circuits.
3. In a telephone system, a plurality of trunk circuits, a hunting switch having access to said trunk circuits, a trunk incoming to said switch including a holding conductor, a means responsive to the seizure of said switch over said incoming trunk for operating it to seize an idle one of said trunk circuits, means in the seized trunk circuit for causing said switch to reoperate to seize a different idle trunk circuit, and means in said switch for maintaining holding potential on said incoming holding conductor during such reoperation.
4. In a telephone system, a plurality of trunk circuits, a hunting switch having access thereto, a trunk incoming to said switch including a holding conductor, means responsive to the seizure of said switch over said incoming trunk for placing holding potential on said incoming holding conductor and for operating said switch to seize an idle one of said trunk circuits, a holding circuit for said switch completed by the seized trunk circuit, means in said trunk circuit for opening said holding circuit, means responsive to said last means for causing the switch to select a different idle trunk circuit, and means for maintaining holding potential on said incoming holding conductor to prevent the release of preceding switches.
5. In a homing type rotary lineswitch having access to a plurality of trunk lines, a trunk including a holding conductor incoming to said switch, means responsive to the seizure of said switch over said incoming trunk for operating the switch to select an idle one of said trunk lines, means in said switch for returning ground

potential over said incoming holding conductor to hold preceding switches operated, a test wiper in said switch grounded by the seized trunk line to hold said switch operated, means responsive to the removal of ground from said test wiper for operating said switch to select the next idle trunk line, means responsive to the release of said incoming trunk for returning said switch to its normal position, and means in said switch for maintaining a continuous ground potential on said incoming holding conductor until said switch has returned to its normal position.

6. In a homing type rotary lineswitch, an incoming trunk including a holding conductor, a plurality of trunk lines accessible to said switch, means responsive to the seizure of said switch over said incoming trunk for operating it to select an idle one of said trunk lines, means in the selected trunk line for causing said switch to select a different idle trunk line, means responsive to the release of said incoming trunk for returning said switch to its normal position, and means for maintaining a continuous ground potential on said incoming holding conductor from the instant the switch is seized until it returns to its normal position.

7. In a rotary hunting switch, a line relay, a slow-acting relay, and a cut-off relay, an operating magnet having interrupter contacts, means responsive to the operation of said line relay when said switch is seized for completing a circuit for said slow-acting relay, for completing a circuit for said magnet through said interrupter contacts, and for shunting said interrupter contacts to hold said magnet energized, a test wiper, and means responsive to the operation of said slow-acting relay for opening the shunt around said interrupter contacts, for opening the initial energizing circuit of said magnet, for extending a self-interrupting circuit for said magnet to said test wiper, for completing a circuit for said cut-off relay, and for extending a shunting circuit for said cut-off relay to said test wiper.

8. In a hunting switch, a line relay, a slow-acting relay, a circuit for said slow-acting relay controlled by said line relay, a rotary magnet having interrupter springs, an operating circuit for said magnet including said interrupter springs, means responsive to the seizure of said switch for closing the operating circuit for said magnet and for operating said line relay, contacts on said line relay for shunting said interrupter springs to hold said magnet energized, and contacts on said slow-acting relay for opening said shunt when said relay operates.

9. In a rotary hunting switch, a line relay and a slow-acting relay, a circuit for said slow-acting relay controlled by said line relay, a magnet having interrupter springs, an operating circuit for said magnet including said interrupter springs, means responsive to the seizure of said switch for completing the operating circuit to said magnet and for energizing said line relay, contacts on said line relay for shunting said interrupter springs to hold said magnet energized, a test wiper, and contacts on said slow-acting relay for opening said shunting circuit, for opening the initial operating circuit of said magnet, and for extending a circuit for said magnet to said test wiper.

EDWARD S. PETERSON.
